UNITED STATES PATENT OFFICE.

MERCER G. YOUNG, OF PITTSFIELD, MASSACHUSETTS, ASSIGNOR TO GENERAL ELECTRIC COMPANY, A CORPORATION OF NEW YORK.

VARIABLE-VOLTAGE TRANSFORMER.

No. 894,714.

Specification of Letters Patent. Patented July 28, 1908.

Application filed December 26, 1907. Serial No. 408,052.

To all whom it may concern:

Be it known that I, MERCER G. YOUNG, a citizen of the United States, residing at Pittsfield, county of Berkshire, State of Massachusetts, have invented certain new and useful Improvements in Variable - Voltage Transformers, of which the following is a specification.

My invention relates to variable-voltage 10 transformers and especially to that class of transformers known as flux-shunt transformers, in which the amount of magnetic flux threading the secondary winding is made to vary by moving a magnetic core or cores.

More particularly, my invention relates to 15 that class of flux-shunt transformers wherein a portion of a magnetic core is surrounded by the primary winding, and in which the secondary winding surrounds the portion of the 20 core surrounded by the primary winding and a second portion of the core not surrounded by the primary winding. There is also a 25 third portion of the core not surrounded by either winding, and the movable magnetic 30 shunt or shunts are so arranged that the flux due to the primary winding may be passed through the secondary winding in only one direction, and hence induce a maximum voltage; or may pass through the secondary 35 windings in two directions and induce a zero voltage. A transformer of this type is shown in Patent No. 865,985.

One object of my invention is to decrease 40 the reactance in the secondary winding of such a transformer, and more particularly when the secondary winding is delivering its maximum possible voltage. I thus improve the operation of these transformers, and do so in the manner which will be described 45 more particularly with reference to the accompanying drawings.

Another object of my invention is the construction of such transformers in a cheap and efficient manner.

My invention will best be understood by 50 reference to the accompanying drawings, in which

Figure 1 is a somewhat diagrammatical side elevation of my invention, the coils being shown in section; Fig. 2 is a top view of the same; and Fig. 3 is an end view on a smaller scale of the variable-reactance coil.

Referring to Fig. 1, 1 shows a magnetic core formed in the usual fashion, with three 55 legs *a*, *b* and *c*, which are magnetically joined

at one end by an end member *d*. Surrounding the central leg *b* is shown a primary winding 2, and surrounding the central leg and the left-hand leg *a* is shown a secondary winding 3. Leads 2' and 3', attached, respectively, to the primary and secondary windings, are shown in the usual fashion. These leads may be connected in the well known way to a source of energy and to suitable translating devices. 4 is an independent coil surrounding leg *a* of the core, and inclosed within secondary winding 3. This is connected by leads 6 to two coils 7 and 7', which are connected in series (Fig. 2). Coils 7 and 7' are hollow, and within the central 60 portions are the legs of two U-shaped cores 8 and 9 of magnetic material. Core 8 is fixed; core 9 is movable in a vertical direction, as is shown in Fig. 1, in one limiting position, with substantially neither of its 65 legs inclosed by coils 7 and 7', and as shown in Fig. 3, in its other limiting position forming with core 8 a substantially closed magnetic circuit threading coils 7 and 7'. 70 Cores 10 and 11 are movable cores of magnetic material. 75 I have shown core 10 attached to a cord 12, which passes over a pulley 13, over another pulley 14, through a hole in core 8, and attached to core 9. I have shown 11 attached to a cord 15, which passes over 80 pulley 13 and is attached thereto by any suitable means, such as a pin 16. I have shown a driving handle 17 suitably attached to pulley 13, so that upon its movement it 85 will cause pulley 13 to revolve and raise and lower cores 10, 11 and 9. Pulleys 13 and 14 are so proportioned and placed that the 90 movable cores may have a vertical movement, and may readily move up and down 95 between legs *a* and *b*, and *b* and *c*, and inside of coils 7 and 7'.

It will be obvious that while I have described a certain method of attaching and moving the movable cores, many other 100 methods may be used, which will be equally as good; the only essential feature of the movement used being that when core 10 is in its highest position, cores 11 and 9 shall be in their lowest position, and that the 105 three cores shall be moved simultaneously or substantially so; cores 11 and 9 moving upward when core 10 moves downward, and that when cores 10 and 9 are in the other limiting position from that shown in Fig. 110

1,—that is, core 10 is in a position similar to that in which core 11 is shown, and core 9 is in the position shown in Fig. 3, core 11 shall be in a position similar to core 10.

5 Fig. 2 shows somewhat more clearly the arrangement of the windings upon the cores, and shows, as previously stated, two reactive coils 7 and 7' connected in series. It will be obvious, however, that if so desired only one 10 reactive coil may be used, or the number of coils may be still further increased, and any suitable connection used between them, so long as winding 4 is short-circuited through the reactive coil or coils.

15 Fig. 3 shows somewhat more clearly the construction of the reactive coils and the core which I prefer; core 9 being shown in the position which gives a maximum reactance in the coil.

20 The operation of the transformer is as follows: In the position of the moving cores shown in Fig. 1, the flux due to the primary winding passes around the closed magnetic circuit formed by leg *b*, core 11, leg *c*, and 25 end member *d*. The secondary winding 3 will then have induced in it its maximum voltage. When the positions of cores 10 and 11 are reversed,—that is, core 11 is drawn up and away from legs *b* and *c*, and core 10 substantially fills the air-space between legs *a* and 30 *b*, above the winding, the magnetic flux induced by the primary winding will pass through the closed magnetic circuit leg *b*, core 10, leg *a* and end member *d*. Secondary 35 winding 3 will then be cut by two substantially equal and opposing fluxes, and no voltage will be induced in it, if there is no magnetic leakage. In the position shown in Fig. 1, if coil 4 were absent or open-circuited, the 40 reactive voltage in secondary winding 3 would be very great, and there would be an excessive impedance. This excessive impedance is due to the fact that the area of the path for the reactive flux is comparatively 45 large and has included within it leg *a*, which is encircled solely by the secondary winding 3, winding 4 being for the moment not considered. This reactance is so great that, unless means are taken to reduce it, a large 50 transformer of this type is practically inoperative. The means whereby I reduce this reactance is by the independent auxiliary winding 4 surrounding leg *a* alone, inside of the secondary winding 3 and connected to a 55 coil or coils of variable reactance. The action of this independent coil is as follows: In the position of the cores shown in Fig. 1, 11 is in the position for maximum voltage and maximum load. The reactive flux due to 60 the secondary winding 3 induces in the auxiliary winding 4 a voltage, and hence a current is produced in winding 4, lead 6, and coils 7 and 7'. The variable reactive coils 7 and 7' have the minimum reactance, as core 65 9 is in a position away from the coils. The

current induced in the winding 4 will, hence, be a maximum, and the reaction of the flux produced by this coil will greatly increase the reluctance of the leakage path for the reactive flux in winding 3, and hence will decrease the total reactive voltage. In the limiting position, reverse to that shown in Fig. 1,—that is, with core 11 raised the full amount and core 10 lowered the full amount, a minimum voltage will be induced in the secondary winding 3. At the same time, core 9 is raised to its full extent, and the reactance of the variable reactive coils 7 and 7' is a maximum. Thus, the current in the auxiliary independent coil 4 and the reactive coils 7 and 7' will be a minimum, and the losses from this source will be reduced. It will be obvious that for intermediate positions of the cores phenomena intermediate to those described will occur.

I do not desire to limit myself to the particular construction and arrangement of parts which I have shown and described, since changes, which do not depart from the spirit of my invention, and which are within the scope of the present claims, will be obvious to those skilled in the art.

What I claim as new and desire to secure by Letters Patent of the United States, is,—

1. The combination, in a variable-voltage transformer having primary and secondary windings, and means for varying the flux due to the primary winding passing through the secondary winding, of means for decreasing the reactance of the secondary winding.

2. The combination, in a variable-voltage transformer having primary and secondary windings, and means for varying the flux due to the primary winding passing through the secondary winding, of an independent coil of variable reactance in inductive relation to the secondary winding.

3. The combination, in a variable-voltage transformer having primary and secondary windings, and means for varying the flux due to the primary winding passing through the secondary winding, of an independent coil in inductive relation to the secondary winding and short-circuited through a coil of variable reactance.

4. The combination, in a variable-voltage transformer having a three-legged core, a primary winding surrounding one leg, a secondary winding surrounding both the leg carrying the primary winding and a second leg, and means for sending the flux due to the primary winding through the other two legs alternately, of means for reducing the reactive voltage in the secondary winding.

5. The combination, in a variable-voltage transformer having a three-legged core, a primary winding surrounding one leg, a secondary winding surrounding both the leg carrying the primary winding and a second leg, and means for sending the flux due to

the primary winding through the other two legs alternately, of an independent coil surrounding the leg surrounded by the secondary winding but not surrounded by the primary winding, and short-circuited through a second coil whose reactance may be varied.

6. The combination, in a variable-voltage transformer having a three-legged core, a primary winding surrounding one leg, a secondary winding surrounding both the leg carrying the primary winding and a second leg, and means for sending the flux due to the primary winding through the other two legs alternately, of an independent coil in inductive relation to the secondary winding short-circuited through a coil of variable reactance whose reactance is a minimum for maximum voltage on the secondary, and a maximum for minimum voltage on the secondary.

7. In combination, a variable-voltage transformer having a three-legged core, a primary winding surrounding one leg, a secondary winding surrounding both the leg carrying the primary winding and a second leg, and two movable magnetic cores, one causing the magnetic flux induced by the primary winding to thread the secondary winding in a single direction, the other causing the magnetic flux induced by the primary winding to thread the secondary winding in two opposite directions, and an independent coil surrounding the leg surrounded by the secondary winding but not surrounded by

the primary winding, and short-circuited through a coil with a magnetic core partly movable, the movable portion producing its greatest effect for a maximum induced voltage in the secondary winding.

8. The combination, in a variable-voltage transformer, of a three-legged core, a primary winding surrounding one leg of said core, a secondary winding surrounding both the leg surrounded by the primary winding and a second leg, an independent coil within the secondary winding surrounding the leg not surrounded by the primary winding, and connected to two other windings in series mounted in a separate core, a portion of which is movable, two movable cores sliding within the legs of the first core, and means for moving these cores in an opposite direction and for simultaneously moving the movable portion of the core surrounded by the auxiliary coils so as to produce a minimum reactance in these coils when the secondary winding has induced in it a maximum voltage, and for producing a maximum reactance in these coils when the secondary windings has induced in it a minimum voltage.

In witness whereof, I have hereunto set my hand this seventeenth day of December, 1907.
